UNITED STATES PATENT OFFICE.

CICERO C. GAITHER, OF JASPER, ALABAMA.

ATTACHMENT FOR POWDER CANS.

Application filed January 28, 1924. Serial No. 689,172.

This invention relates to a faucet for powder kegs, the general object of the invention being to provide means for removing the closure from the keg by a wooden member and to so form this member that it can be used as a stopper for the faucet.

Another object of the invention is to provide simple means for clamping the faucet in the opening in the keg.

10 This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying drawings wherein like characters denote like 20 or corresponding parts throughout the several views, and in which:

Figure 1 is a view of a powder keg showing the invention in use.

Figure 2 is a longitudinal sectional view. 25 Figure 3 is a view taken at right angles to Figure 2, and showing the parts in elevation.

Figure 4 is a view taken a half turn from Figure 3.

30 Figure 5 is a transverse sectional view through Figure 1.

Figure 6 is a view of the stopper.

Figure 7 is a view similar to Figure 5 showing the parts in another position.

35 Figure 8 is a perspective view of a portion of a powder can with which the device may be used.

In these views 1 indicates the wooden faucet which has a reduced end 2 for fitting in the hole in the keg or can. A lip 3 is formed on this end which provides a groove 4 for engaging one wall of the opening in the keg. A block 5 is slidably connected with the base of the faucet by the bolt 6 which passes through a slot 7 in the block and said block is formed with a jaw 8 which cooperates with the lip for clamping the faucet to the keg. A gasket 9 may be provided for holding the faucet tightly in the opening. A stopper 10 also formed of wood and having a head 11 and a pointed end 12 is provided for closing the faucet. The pointed end of this stopper is used for removing the closure from the keg. A gate 13

is also provided for closing the faucet, said 55 gate passing through a slot 14 in the body of the faucet, and being connected to a pivoted lever 15 which is held by a spring 16 in a position with the gate closed. The stopper is provided with a groove 17 for receiving part of the gate which acts to hold the stopper in place.

The closure is removed from the keg by the stopper by holding the stopper in the left hand and placing its pointed end against the 65 clamp *a* that holds the closure *b* of the keg or can *A* in place. The head of the stopper is then struck with the other hand so as to release the clamp. The other clamp is then 70 released in the same manner. The pointed end is then placed behind the corner of the lid *b* and then the head is again struck with the hand which slides the lid towards the center of the keg. The faucet is then placed in the mouth or opening and clamped therein 75 as before described. Both the gate and the stopper can be used to close the faucet.

It is thought from the foregoing description that the advantages and novel features 80 of my invention will be readily apparent.

I desire it to be understood that I may make changes in the construction and in the combination and arrangement of the several parts, provided that such changes fall within the scope of the appended claim.

What I claim is:

A closure of the character described including a body having a longitudinal bore, means for detachably clamping the same in an opening in a keg, said body having a 90 transverse slot extending inwardly from one side thereof to a point slightly beyond one side of the bore, a horizontally movable gate member normally having one end thereof in the slot and having an opening in the other 95 end, an angular pivoted lever mounted upon the body with one end loosely engaged within the opening at the outer end of the gate and the other end of said lever disposed for rocking the lever upon its pivot and a 100 spring engaging member at one end of the lever for normally urging the gate member in a direction toward the inner end of the slot whereby the same may be disposed transversely of the bore or moved into contact with a member within the bore.

In testimony whereof I affix my signature.

CICERO C. GAITHER.
